UNITED STATES PATENT OFFICE

WILLIAM F. M. HAWE, OF CRAFTON, PENNSYLVANIA, ASSIGNOR TO E. L. SILVERMAN, OF NEW YORK, N. Y.

DESIGN FOR A COMBINED RAZOR HOLDER AND SHARPENER

Application filed January 16, 1932. Serial No. 42,509. Term of patent 7 years.

To all whom it may concern:

Be it known that I, WILLIAM F. M. HAWE, a citizen of the United States, and residing at Crafton, county of Allegheny, and State of Pennsylvania, have invented a new, original, and ornamental Design for Combined Razor Holder and Sharpener, of which the following is a specification, reference being had to the accompanying drawings, forming part hereof, and in which

Fig. 1 is a perspective view showing a combined razor holder and sharpener embodying my new design, and

Fig. 2 is a perspective view disclosing the bottom of the combined razor holder and sharpener.

I claim:

The ornamental design for a combined razor holder and sharpener substantially as shown.

WILLIAM F. M. HAWE.
